DESIGN FOR A FIELD GLASS

George Dobrusin, Chicago, Ill.

Application August 21, 1939, Serial No. 86,821

Term of patent 14 years

To all whom it may concern:

Be it known that I, George Dobrusin, a citizen of the United States, residing at Chicago, in the county of Cook and State of Illinois, have invented a new, original, and ornamental Design for a Field Glass, of which the following is a specification, reference being had to the accompanying drawing, forming a part thereof.

Fig. 1 is a front elevation of a field glass embodying my new design.

Fig. 2 is a top plan view of the same.
Fig. 3 is a rear elevation of the same.
Fig. 4 is a bottom plan view of the same.
Fig. 5 is a side elevation taken as indicated by the line 5—5 in Fig. 1.

I claim:

The ornamental design for a field glass, substantially as shown.

GEORGE DOBRUSIN.
